CLAIM

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image;

FIG. 6 is a rear perspective view thereof;

FIG. 7 is a rear perspective view in a condition that the mobile phone is folded in half;

FIG. 8 is a front view of FIG. 7;

FIG. 9 a rear view of Fig. 7;

FIG. 10 is a left side view of FIG. 7 where the right side view is a mirror image;

FIG. 11 is a top plan view of FIG. 7; and,

FIG. 12 is a bottom plan view of FIG. 7.

The broken lines depict portions of the mobile phone that form no part of the claimed design.
